UNITED STATES PATENT OFFICE

173,073

VOLTAGE SOURCE AND CONTROL CABINET

James C. Marsh and Norman S. Curtis, Indianapolis, Ind., assignors to Ransburg Electro-Coating Corp., Indianapolis, Ind., a corporation of Indiana

Application March 1, 1952, Serial No. 18,743

Term of patent 14 years

(Cl. D26—5)

To all whom it may concern:

Be it known that we, James C. Marsh, a citizen of the United States and resident of the city of Indianapolis, in the county of Marion and State of Indiana, and Norman S. Curtis, a citizen of the United States and resident of the city of Indianapolis, in the county of Marion and State of Indiana, have invented a new, original, and ornamental Design for a Voltage Source and Control Cabinet, of which the following is a specification, reference being had to the accompanying drawing, forming part thereof.

Fig. 1 is a perspective view of the voltage source and control cabinet, showing our new design;

Fig. 2 is a plan view thereof; and

Fig. 3 is a transverse sectional view thereof on the plane of line 3—3 of Fig. 2.

The back and right side of the cabinet, not shown in the drawing, are essentially plain, except that the upper back side contains a rectangular opening as shown in Figs. 1 and 3.

We claim:

The ornamental design for a voltage source and control cabinet, as shown and described.
